CLAIM

The ornamental design for a printer as shown and described.

DESCRIPTION

FIG. 1 is a front view of a printer showing my new design;
FIG. 2 is a rear view thereof;

FIG. 3 is a top plan view thereof;

FIG. 4 is a bottom plan view thereof;

FIG. 5 is a left side view thereof;

FIG. 6 is a right side view thereof;

FIG. 7 is a perspective view thereof;

FIG. 8 is an enlarged end view of a portion defined by 8-8
line in FIG. 1, cut along 8'-8' line in FIG. 5;

FIG. 9 is an enlarged end view of a portion defined by 9-9
line in FIG. 1, cut along 9'-9' line in FIG. 5;

FIG. 10 is an enlarged end view of a portion defined by
10-10-10 lines in FIG. 5, cut along 10'-10' line in FIG. 1;
and,

FIG. 11 is an enlarged end view of a portion defined by 11-11
line in FIG. 5, cut along 11'-11' line in FIG. 1.

The evenly spaced broken lines depict portions of the printer
which form no part of the claimed design. The dot-dash
broken lines depict the bounds of the cross-section views,
are for reference purposes only, and form no part of the
claimed design.

1 Claim, 8 Drawing Sheets
